(57) **CLAIM**

The ornamental designs for a vented bottle spout, as shown and described.

DESCRIPTION

FIG. 1 is a perspective view of the vented bottle spout of the invention, showing one ventilation hole.

FIG. 2 is a side view of the vented bottle spout of FIG. 1.

FIG. 3 is a top view of the vented bottle spout of FIG. 1.

FIG. 4 is a bottom view of the vented bottle spout of FIG. 1.

FIG. 5 is a cross-section view of the vented bottle spout of FIG. 1.

FIG. 6 is a perspective view of a second embodiment of a vented bottle spout, showing two ventilation holes.

FIG. 7 is a side view of the vented bottle spout of FIG. 6.

FIG. 8 is a top view of the vented bottle spout of FIG. 6.

FIG. 9 is a bottom view of the vented bottle spout of FIG. 6.

FIG. 10 is a cross-section view of the vented bottle spout of FIG. 6.

FIG. 11 is a perspective view of a third embodiment of a vented bottle spout, showing three ventilation holes.

FIG. 12 is a side view of the vented bottle spout of FIG. 11.

FIG. 13 is a top view of the vented bottle spout of FIG. 11.

FIG. 14 is a bottom view of the vented bottle spout of FIG. 11.

FIG. 15 is a cross-section view of the vented bottle spout of FIG. 11.

FIG. 16 is a perspective view of a fourth embodiment of a vented bottle spout, showing four ventilation holes.

FIG. 17 is a side view of the vented bottle spout of FIG. 16.

FIG. 18 is a top view of the vented bottle spout of FIG. 16.

FIG. 19 is a bottom view of the vented bottle spout of FIG. 16; and,

FIG. 20 is a cross-section view of the vented bottle spout of FIG. 16.
